UNITED STATES PATENT OFFICE.

JEREMIAH A. SCRIVEN, OF NEW YORK, N. Y.

DESIGN FOR A BIFURCATED NETHER GARMENT.

SPECIFICATION forming part of Design No. 31,660, dated October 10, 1899.

Application filed September 13, 1899. Serial No. 730,388. Term of patent 14 years.

To all whom it may concern:

Be it known that I, JEREMIAH A. SCRIVEN, a citizen of the United States, residing in the borough of Manhattan, in the city, county, and State of New York, and whose post-office address is No. 18 East Fifteenth street, in said city, have invented and produced a new and original Design for Bifurcated Nether Garments, of which the following is a specification.

The essential characteristics of my design consist in insertions or panels in the front of the garment, which insertions extend each in a continuous length from the lower portion 15 of each of the tubular members of the garment and throughout the body portion thereof to substantially the upper end, each of said insertions likewise extending laterally from substantially the inner seam of a tubular member of the garment to substantially the outer side thereof.

In the accompanying drawing the figure represents a front view of a garment embodying my design.

25 A indicates the front of the body portion

of a bifurcated nether garment from which extend tubular members B. Let into the front portion of the garment are two insertions or panels, each of which comprises a portion a, which extends in a longitudinal direction substantially throughout the length of a tubular member B of the garment, and a portion b, which is continuous with the portion a and extends throughout the body portion of the garment to substantially the upper end thereof. These insertions or panels a b each extend in a lateral direction from substantially the inner seam c of a tubular member B to substantially the outer side d thereof. The ribs or wales e of the panels 30 extend continuously in a longitudinal direction from the lower to the upper end of each panel.

What I claim is—

The design for a bifurcated nether garment 45 substantially as herein shown and described.

JEREMIAH A. SCRIVEN.
